UNITED STATES PATENT OFFICE

HERMANN MALY, OF GUBEN, GERMANY

TREATING DRY WEBS OF WOVEN MATERIAL

Application filed May 2, 1928, Serial No. 274,582, and in Germany May 10, 1927.

The invention relates to a method of and a machine for moistening, chemically treating, and steaming dry webs of woven material.

5 In the dry, and particularly in the hot refinement or dressing of the webs of woven material there has always been up to now the noxious result that the web becomes exceedingly dry. To compensate as far as possible 10 this noxious condition, the known moistening processes have been employed hitherto, which consist either in artificially moistening the air, or leading the exceedingly dry webs along moist surfaces without touching the same, 15 or in sprinkling the web faces with finely atomized water, or inserting the dry webs between moistened cloths.

The two first-named processes suffer from the drawback, that a further drying of the 20 dry web, which is warmer than the surrounding air, takes place until a state of equalization of temperature arises between this dry and warmer web and the air. Only from this 25 moment begins the hygroscopic action, and this only to a degree corresponding to the moisture contained in the air.

The two last-named processes suffer from the well-known drawback that previous dressing effects, as e. g. pressing effects, are destroyed by them, and that these processes 30 therefore can be employed only within narrow limits.

Now my present invention relates on the one hand to a process for moistening, by a 35 simultaneous capillary and hygroscopic action, exceedingly and normally dry webs, to such an extent, that the subsequent dressing process up to the hot-pressing just consumes the moisture contained in the web, and, on the 40 other hand, to a method and apparatus for applying water or chemical agents to exceedingly or normally dry webs, with simultaneous capillary, hygroscopic, and osmotic action, without moistening the web to such an 45 extent, that a special subsequent drying operation is required.

To carry out my new process, I employ a machine as illustrated in the drawing, that accompanies and forms part of this specification.

The figure shows a front view of the machine.

The machine illustrated possesses two rollers w^1 , w^2 , that alternately act as magazine and receiving rollers. The rollers w^1 and w^2 are driven respectively by drive shafts b^1 and b^2 . First the wrapping cloth l is wound on roller w^1 from roller w^2 , and then it is wound on roller w^2 from roller w^1 . The rollers w^1 , w^2 are designed as perforated metallic hollow rollers. The wrapping cloth l receives its driving motion from a pair of pressure rollers d^1 , d^2 . The motion of the wrapping cloth is constant; that of the winding rollers w^1 , w^2 is accomplished by a leading friction drive. Besides imparting motion, the pair of pressure rollers d^1 , d^2 serves at the same time to evenly distribute the moisture taken up by the wrapping cloth. The degree of moisture of the wrapping cloth may be regulated by varying the speed of rotation of the moistening roller a .

The machine is further provided with a suction or pressure pump p , which is connected through pipes c^1 , c^2 with the perforated hollow rollers w^1 , w^2 . The latter may also be connected to a steam supply.

The process the described machine is intended for, takes place in the following manner:

The dry webs x , y are wrapped into the wrapping cloth l that is moistened with water or a suitable solution. During or after the wrapping procedure the air pump p is started. An equalization of the moisture contained in excess in the wrapping cloth l then takes place between the latter and the dry webs x , y . This equalization takes place both through capillary action, as the two dry surfaces of each of the webs x , y are in close contact with the moist surfaces of the wrapping cloth l , and through hygroscopic action, as the air current set up by the air pump p as suction or pressure current, is forced to first pass through the moist layers of the wrapping cloth l , before passing through the layers of the dry webs x , y . The air current cools down on passing the moist wrapping cloth and becomes saturated with moisture, and the dry web, that is hotter than the moist cloth, is

likewise cooled down, and this more quickly. Hence, the moist air robs the hotter dry web of the high insulating capacity it possesses due to its high dry heat, whereby the equalization of moisture and heat between the moist cool wrapping cloth and the hot dry web is particularly facilitated.

The described process also affords the peculiar effect, that, even when employed in a shortened manner, that is, when less moisture is to be applied to the web than corresponds to the coefficient of equalization between the wrapping cloth and the web, this smaller amount of moisture is applied not only on the surface, but internally.

My described process is applicable further as a new steaming process in so far as the moisture imparted to each of the rolls, 20 consisting of the wrapping cloth and the web, on the perforated hollow cylinders w^1 , w^2 , may be evaporated by high pressure steam or hot air, led through the roll. This steam produced from the moisture in the roll itself is used for steaming the material, while in contradistinction thereto, in the hitherto known dry steaming process, fresh high pressure steam is used.

After steaming the web, the surplus moisture is drawn off in the form of steam by the air pump p , until a suitable cooled state has been reached, by the air pump p .

Due to the hitherto known dry steaming process operating with high pressure steam, 35 the web was exceedingly dried and overheated. This noxious effect cannot arise with my hereinbefore described process, as the moisture introduced in the roll, is evaporated, whereby the web is protected from becoming exceedingly dry and overheated. 40 This is an important advantage that is afforded by my process.

What I claim, is:—

1. The process of treating dry webs of 45 woven material consisting in moistening a wrapping cloth, forming the cloth and web into a roll in alternate layers, and leading a gaseous agent through the roll to uniformly transmit the moisture in the cloth to the web.

2. The process of treating dry webs of woven material consisting in moistening a wrapping cloth, forming the cloth and web into a roll in alternate layers, and leading 55 steam through the roll to uniformly transmit the moisture in the cloth to the web.

3. The process of treating hot dry webs of woven material consisting in moistening a wrapping cloth, forming the cloth and web 60 into a roll in alternate layers, and leading a gaseous agent through the roll to uniformly transmit the moisture in the cloth to the web.

4. The combination for treating dry webs 65 of woven material of a perforated hollow

roller, a wrapping cloth, means for winding said dry web accompanied by said wrapping cloth on said roller, means for moistening said wrapping cloth prior to its being wound with said dry web on said roller, and means for sending a gaseous agent through said roller, wrapping cloth, and woven web.

5. The combination for treating dry webs of woven material of a perforated hollow 75 roller, a wrapping cloth, means for winding said dry web accompanied by said wrapping cloth on said roller, means for moistening said wrapping cloth prior to its being wound with said dry web on said roller, and means for sending steam through said roller, wrapping cloth, and woven web.

6. The combination for treating dry webs of woven material of a perforated hollow 85 roller, a wrapping cloth, means for winding said dry web accompanied by said wrapping cloth on said roller, means for moistening said wrapping cloth prior to its being wound with said dry web on said roller, means for regulating the amount of moisture taken up by said wrapping cloth, and means for sending a gaseous agent through said roller, wrapping cloth, and woven web.

In testimony whereof I affix my signature. 95
HERMANN MALY.
